UNITED STATES PATENT OFFICE.

SAMUEL N. GOODMAN, OF PHILADELPHIA, PENNSYLVANIA, ASSIGNOR TO
FRIEDBERGER-AARON MANUFACTURING COMPANY, OF PHILADELPHIA,
PENNSYLVANIA, A CORPORATION OF PENNSYLVANIA.

DESIGN FOR TRIMMING.

49,475.

Specification for Design.

Patented Aug. 1, 1916.

Application filed May 29, 1916. Serial No. 100,728. Term of patent 7 years.

To all whom it may concern:

Be it known that I, SAMUEL N. GOODMAN, a citizen of the United States, residing in Philadelphia, county of Philadelphia, and State of Pennsylvania, have invented a new, original, and ornamental Design for Trimming, of which the following is a specification, reference being had to the accompanying drawings, which form a part thereof.

The drawing is a plan view of a portion of the trimming showing my design.

The same comprises a sewing-on edge *a*, a pair of threads *b* spaced apart and extending longitudinally in a zigzag direction between the sewing-on edge and the opposite

edge of the trimming, sets of threads *c* arranged to form series of transversely extending loops within the angles formed by the outer of the two threads *b*, and a distinctive background *d* formed of relatively fine threads having a nubia stitch or effect.

I claim—

The ornamental design for a trimming as shown and described.

In testimony of which invention, I have hereunto set my hand, at Philadelphia, on this 26th day of May, A. D. 1916.

SAMUEL N. GOODMAN.
